MULTIPURPOSE BAND METAL
FABRICATING TOOL

Karl A. Bohn, 109-16 222nd St., Queens Village, N.Y.
11429, and Francis Shaw, East Hampton, N.Y.; said
Francis Shaw assignor to Karl A. Bohn

Filed July 3, 1972, Ser. No. 268,652

Term of patent 14 years

Int. Cl. D8—05

U.S. Cl. D8—55

FIG. 1 is a front-side perspective view of a multipurpose band metal fabricating tool showing our new design.

FIG. 2 is a side elevation view of the other side thereof.

We claim:

The ornamental design for a multipurpose band metal fabricating tool, substantially as shown.
